UNITED STATES PATENT OFFICE.

JOHN R. JONES, OF OSHKOSH, WISCONSIN.

SCAFFOLD-LADDER.

No. 921,117.

Specification of Letters Patent.

Patented May 11, 1909.

Application filed September 16, 1907. Serial No. 393,256.

To all whom it may concern:

Be it known that I, JOHN R. JONES, residing in Oshkosh, in the county of Winnebago and State of Wisconsin, have invented new 5 and useful Improvements in Scaffold-Ladders, of which the following is a description, reference being had to the accompanying drawings, which are a part of this specification.

10 This invention has for its object to provide a scaffold ladder adapted for supporting a scaffold in a horizontal position by means of brackets, said brackets being adjustable in position to permit the scaffold being located 15 beneath or on top of the ladder as found most convenient.

Another object of this invention is to provide a scaffold bracket which will be capable of adjustment on the ladder by a person 20 standing at the foot of the ladder or on the ladder itself or on the scaffold, said bracket being capable of securely engaging the ladder in its various adjustments to prevent accidental movement.

25 Another object of the invention is to accomplish the above objects by means of a bracket slidably mounted on the ladder and having a rope controlled latch for engaging the ladder rungs, the supporting arms of said 30 bracket being jointed and adjustably connected with the bracket frame so as to alter the angle of the bracket with relation to the ladder and permit the scaffold carried thereby to remain horizontal whether it is above 35 or beneath the ladder.

Another object of this invention is to provide a clamp for splicing the ends of ladder sections together by engaging the rungs of the ladder sections between two clamping 40 members, and causing said clamping members to forcibly tighten thereon by means of cam engagements between them operated by a screw moving one clamping member with relation to the other, said splicing clamp being 45 designed to effectively clamp the ladder sections together without interfering with the operation of the adjustable scaffold bracket.

With the above and other objects in view 50 the invention consists in the scaffold ladder herein claimed, its parts and combinations of parts and all equivalents.

Referring to the accompanying drawings in which like characters of reference indicate 55 the same parts in the several views; Figure 1 is a sectional elevation of a scaffold ladder

constructed in accordance with this invention, having the scaffold bracket in position for supporting the scaffold beneath the ladder; Fig. 2 is a side elevation thereof showing the scaffold bracket in position for supporting the scaffold above the ladder, and Fig. 3 is a front elevation of the ladder as shown in Fig. 1.

In these drawings 10 represents a ladder 65 section of usual construction, preferably provided with rollers 11 at its upper end to ride upon the wall, and having a pulley 12 secured between a pair of cross pieces 13 similar to rungs at its end around which pulley passes a 70 hoisting rope 14. One end of the hoisting rope connects with the top rod 15 of a bracket frame which is made up of a series of round horizontal cross rods 15, of which the above mentioned is one, and side pieces 16, 75 the cross pieces bearing upon the side rails of the ladder and being longer than the entire width of the ladder so that the side pieces are outside of the side rails of the ladder. The side pieces 16 are connected by U-shaped 80 bolts or clamps 17 with back pieces 18 which extend across the back of the ladder and bear against the side rails, there being blocks 19 within the U-shaped bolts and between the back pieces 18 and the side strips 16 to properly space the back pieces from the front portion of the frame. By means of this construction a strong frame is provided which is freely slidable on the ladder without binding.

Besides the round cross pieces 15 the 90 bracket frame is provided at an intermediate portion with a pair of parallel cross pieces 20 which are square in cross section, and to the rear of which are secured blocks 21 to be engaged by a pair of latches 22 which are pivot- 95 ed in the frame by being mounted on one of the round cross pieces 15 loosely mounted in the side pieces so as to be free to turn. This round cross piece 15 on which the latches are mounted is desirably spring pressed by 100 means of a coil spring 22' surrounding it so as to normally hold the latches in engagement with the blocks 21. The latches 22 are preferably of a hook shape to engage the rungs of the ladder as shown in Figs. 1 and 2 and lock 105 the frame against a downward movement.

The latches 22 have forwardly extending projections 23 to which is connected the end of a rope 24 which passes over a pulley 25, preferably on the side rail near the top of the 110 ladder, and then beneath the lower rung of the ladder, as with rope 14, and then to the

projection 23 where it is again connected. The end of the hoisting rope 14 after passing beneath the lower rung of the ladder connects with one of the lower cross pieces of the 5 bracket frame.

One of the round cross pieces 15 of the bracket frame end has the two side pieces of the bracket member 26 pivotally mounted thereon by means of looped metal straps 27 10 secured to said member and surrounding the cross piece. This bracket member 26 has its side pieces connected by cross pieces to form a frame for supporting a scaffold, and a bolt 28 in its outer end pivotally connects a brace 15 member 29 thereto, the bolt passing through the side pieces of the bracket member 26 and of the brace member 29, which together form the bracket of the bracket frame 16. There are preferably rollers 30 mounted on the bolt 20 28 and spaced apart by a sleeve 31 to prevent the bracket scraping against the wall. The brace frame 29 is made up of the side pieces and the cross pieces, similar to the bracket frame 26, and the lower ends of its side pieces 25 are forked to receive any one of the cross pieces 15 at the lower part of the bracket frame 16, there being curved metal strips 32 secured to the back of these ends to securely engage the rear of the cross pieces 15 and 30 hooks 33 pivoted to these ends to securely engage the front of the cross pieces, the hooks 33 being preferably of sheet metal and gravity operated by reason of their shape and the location of their pivot, so that they normally close upon the cross pieces 15 in any 35 operative position of the ladder. The hooks are confined in their movements by stop pins 34 and have outwardly turned upper ends to form projections 35 by which they may be 40 swung out of engagement for the purpose of changing the adjustment of the bracket.

When a ladder is used for supporting a scaffold at the greatest height, the ladder is turned so that the bracket will be on top 45 thereof as shown in Fig. 2, and then the brace member 29 is engaged with one of the lower cross pieces 15 to make the bracket member 26 approximately horizontal. In this position of the bracket it may be run up 50 to very near the extreme upper end of the ladder, the scaffold being supported on the brackets of a pair of such ladders by resting upon the bracket members 26. As the work progresses and it is desired to lower the scaffold, the rope 14 at the back of the ladder is first pulled downwardly so as to slightly lift the bracket frame and clear the latches 22 55 from the rung of the ladder with which it was engaged, then the rope 24 at the back of the ladder is pulled downwardly to cause the latches 22 to swing against the action of their spring so as to clear the line of the rungs, and then by allowing the bracket to descend on the ladder by gravity with the 60 latch held released by means of its rope 24

and controlling the speed of descent by means of the rope 14 the bracket may be lowered to any desired position and again locked by releasing the rope 24 so that the spring returns the latches to the position shown in 70 Figs. 1 and 2 where they will engage a rung of the ladder and be braced by the blocks 21 to securely lock the bracket in place. As the brackets are lowered on their ladders the scaffold supported thereby naturally moves 75 farther away from the wall of the building by reason of the inclined position of the ladders, and to prevent inconvenience arising from this cause, each ladder may be reversed so as to bring the bracket beneath it or between it and the wall, as shown in Fig. 1, and then by changing the engagement of the brace member 29 from the lower cross piece 15 to a higher one the angle of the bracket 80 may be changed to cause the bracket member 85 thereof to return to a horizontal position and the scaffold may thus be supported nearer to the building than when the bracket remains above the ladder. In order that the ladder of this invention may further avoid 90 forming too great a distance between the wall and the scaffold, it is made in sections by which it may be shortened from time to time as the work progresses, and to have a splicing 95 means for the sections of the ladder which will not interfere with the travel of the bracket frame, I have provided the ladder splicing clamp shown in Figs. 3, 4 and 5. This splicing clamp comprises a pair of 100 clamping members 36 and 37 having engaged cam hooks 38 at regular intervals. The clamping members are adapted to receive the rungs 39 of the ladder between them and between the cam hooks 38 of clamping member 37 and cross pieces 40 105 thereon, which latter extend to the side rails of the ladder and bear thereon. The clamping member 37 has a clamping screw 41 threaded in a projection thereof and bearing on the clamping member 36 so as to cause 110 them to move with relation to each other in a direction to force the pairs of cam hooks 38 together and result in clamping the clamping members tightly upon the rungs of the ladder therebetween. This ladder splicing clamp is 115 connected with the rungs of the meeting ends of two ladder sections so that they are firmly held together, their side rails having their 120 ends fitting in tubular metal sleeves 42. This splicing means does not interfere with the operation of the bracket frame as the side pieces of the brace frame 29 will pass on opposite sides of the clamping members 36 and 37 and the sleeves 42 may be freely passed by the bracket frame.

When it is desired to raise the bracket frame the latch rope 24 need not receive attention, as it is only necessary to pull down upon the hoisting rope 14 at the rear of the ladder and thereby lift the bracket frame, 130

the latches 22 on striking the rungs of the ladder being forced to swing against the action of their spring until they clear the rung and spring into position to engage it on the 5 upper side thereof.

When the ladder is made up of several sections the ropes are correspondingly lengthened so as to reach to near the ground and permit of the change in position of the scaffold 10 by a person standing on the ground. When desired the single ladder section containing the bracket may be suspended from a main inclined ladder so that said ladder section will hang vertically, and thus further assure 15 the scaffold remaining at a definite distance from the wall.

What I claim as my invention is;

1. A scaffold ladder, comprising a ladder member, a bracket frame slidably mounted 20 thereon, and provided with a series of cross pieces, a bracket member provided with loop straps pivotally connecting it with one of the cross pieces of the bracket frame, and a brace member pivotally connected therewith and provided with means for releasably 25 engaging one or another of the cross pieces of the bracket frame for varying the angle of the bracket member.

2. A scaffold ladder, comprising a ladder member, a bracket frame slidably mounted 30 thereon and provided with a series of cross pieces, a bracket member pivotally connected on one of the cross pieces of the bracket frame, a brace member pivotally 35 connected therewith and formed at its lower end to fit one or another of the cross pieces, metal plates on the brace member engaging the cross pieces of the bracket frame when the brace member is engaged therewith, and 40 gravity hooks on the brace member for also

engaging said cross pieces and coöperating with the metal plates to hold the brace member in its adjustments on the bracket frame.

3. A scaffold ladder, comprising a pair of ladder members, a bracket frame slidably 45 mounted thereon, a bracket carried by the bracket frame, means for moving the bracket frame and holding it in its adjusted positions, and a splicing clamp for locking the ladder members together end to end without interfering with the movements of the bracket frame, comprising a pair of clamping members having coöperating cam hooks, and a screw mounted on one clamping member and 50 engaging the other clamping member for causing them to tightly clamp the rungs of the ladder members between them.

4. A scaffold ladder, comprising a pair of ladder members, a bracket frame slidably mounted thereon, a bracket carried by the 55 bracket frame, means for moving the bracket frame on the bracket members and for holding it in its adjusted positions thereon, sleeves receiving the ends of the side rails of the ladder members and a ladder splicing clamp 60 consisting of a pair of clamping members having coöperating cam hooks, cross pieces on one of the clamping members to engage the side rails of the ladder members, and a screw on one clamping member engaging 65 the other clamping member for causing the cam hooks to draw the clamping members together and clamp the rungs of the ladder members between them.

In testimony whereof, I affix my signature, in presence of two witnesses.

JOHN R. JONES.
